UNITED STATES PATENT OFFICE.

GEORGE W. CRANE, OF MINNEAPOLIS, MINNESOTA, ASSIGNOR TO THE PAIGE MANUFACTURING COMPANY, OF PAINESVILLE, OHIO.

HORSE-POWER.

SPECIFICATION forming part of Letters Patent No. 340,938, dated April 27, 1886.

Application filed January 11, 1886. Serial No. 188,184. (No model.)

To all whom it may concern:

Be it known that I, GEORGE W. CRANE, a citizen of the United States, and a resident of Minneapolis, in the county of Hennepin and 5 State of Minnesota, have invented certain Improvements in Horse-Powers, of which the following is a specification.

My invention relates to improvements in horse-powers that are applicable for general 10 use, but are especially adapted for elevator purposes.

The invention consists, generally, in the construction and combination hereinafter described, and particularly pointed out in the 15 claim.

In the accompanying drawings, forming part of this specification, Figure 1 is a sectional side elevation, and Fig. 2 is an end elevation, of a machine embodying my invention.

20 In the drawings, A represents the sills of the frame. To these sills are secured the upright posts or standards B. A cross beam, C, is secured to the upper ends of the standards B. The standards B and cross-beam C are 25 securely braced by the diagonal rods D, whose upper ends are spiked or bolted to the beam C, and whose lower ends are spiked or bolted to the sills A. A cross-sill, E, extends across the frame upon one side of the posts B, as 30 shown in Fig. 1.

F is an upright shaft whose upper end passes through a box, S, that is secured to the side of the cross-beam C, and whose lower end is seated in a step, G, that is located on the top 35 of the sill E, upon the top of this shaft the sweep-head is fastened by any suitable means.

The horizontal master-wheel H is mounted upon the shaft F. This wheel is made of large size and extends nearly to the sides of the 40 frame.

I is a horizontal shaft whose inner end is journaled in a box, K, that is fastened upon the sill E. The outer end of the shaft is journaled in a box, L, that is secured to the top 45 of the sill A.

J is a bevel-pinion on the shaft I, that meshes

with the master-wheel H. As the master-wheel is of large size, it is necessary to hold it firmly upon the pinion J. For this purpose I provide an arched bridge-tree, M, that is secured to the frame A, which is formed with a sleeve or collar, R, through which passes a stud, S. Upon this stud is mounted an idler, N, that bears upon the upper surface of the master-wheel directly over the pinion J. The 50 shaft I passes under the arch of the bridge-tree, as shown in Fig. 2. This shaft is coupled to a tumbler-rod, O, by a universal joint, P.

By locating beam C and sill E with relation to each other as shown, it permits the boxes 55 for shafts F and I to be readily put in place and removed when necessary, and simplifies and cheapens the construction. The sleeve or collar R also strengthens the connection of the idler N to the arch. The result of all is 60 that a most efficient horse-power is formed, the parts of which can be readily put up and taken down.

I claim as my invention—

The within - described horse - power, composed of a frame, A, beam C, braced by bars D, cross-sill E, located with reference to beam C substantially as shown, box S, secured to the side of said beam, step G, secured to the top of said sill, shaft F, carrying master-wheel H 75 and journaled in said box and step, boxes K and L, secured, respectively, to said sill and frame A, shaft I, carrying pinion J, meshing with the master-wheel and journaled in boxes K and L, the arch M, straddling box L and 80 formed with sleeve R, and the stud S, carrying idler N, to bear on the master-wheel above pinion J, the said several parts being relatively arranged substantially as shown and described. 85

In testimony whereof I have hereunto set my hand this 6th day of January, 1886.

GEORGE W. CRANE.

In presence of—

CHAS. L. JAMES,
A. C. PAUL.
